US00D716726S

(12) **United States Design Patent**
Workman et al.

(10) **Patent No.:** US D716,726 S
(45) **Date of Patent:** ** Nov. 4, 2014

(54) **ENERGY STORAGE AND POWER SUPPLY DEVICE**

(75) Inventors: **Robert E. Workman**, Morgan, UT (US); **Norm Krantz**, Logan, UT (US); **Joseph R. Atkin**, Highland, UT (US); **Walker Ford**, Bluffdale, UT (US)

(73) Assignee: **Goal Zero LLC**, Bluffdale, UT (US)

(**) Term: **14 Years**

(21) Appl. No.: **29/410,374**

(22) Filed: **Jan. 6, 2012**

(51) **LOC (10) Cl.** 13-02

(52) **U.S. Cl.**

(57) **CLAIM**

We claim the ornamental design for an energy storage and power supply device, as shown and described.

DESCRIPTION

FIG. 1 is a front perspective view of an energy storage and power supply device showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines shown represent unclaimed subject matter and form no part of the claimed design.
